CLAIM

The ornamental design for a case for laptop-shaped portable electronic computing device, as shown and described.

DESCRIPTION

FIG. 1 is a front perspective view of a case for laptop-shaped portable electronic computing device.

FIG. 2 is a front elevational view thereof.

FIG. 3 is a rear plan elevational thereof.

FIG. 4 is a top elevational view thereof.

FIG. 5 is a bottom elevational view thereof.

FIG. 6 is a left elevational view thereof; and,

FIG. 7 is a right elevational view thereof.

The features shown in broken lines in the drawing figures depict features that form no part of the claimed design.

1 Claim, 3 Drawing Sheets
